CABLE CONNECTOR

Homer P. Chandler, Mansfield, Ohio, assignor to
The Ohio Brass Company, Mansfield, Ohio, a
corporation of New Jersey

Application May 25, 1940, Serial No. 337,221

3 Claims. (Cl. 173—328)

My invention relates to connectors of the type for connecting the ends of cables and is particularly adapted for use in mines, although use in other places may be made of the same.

One object of my invention is to provide a two part connector in which the casing of each part is molded in one piece from elastic, flexible and deformable material.

Another object of my invention is to provide a connector in which the contacts are easily removable through the rear ends or entrance ends of the connector parts.

Another object of my invention is to provide a two part connector provided with means to either draw or hold the parts together.

A further object of my invention is to provide a connector part in which the casing is split and may be spread apart at its rear or cable entrance end to facilitate removal of the contacts for connection to the cable conductors and easy reinsertion of the contacts after connection to the conductors.

Further objects of my invention will be disclosed as I proceed with a description of my invention.

My invention resides in the new and novel construction, combination and relation of the parts hereinafter described and shown in the accompanying drawing.

In the drawing:

Fig. 1 is a side view in partial section of my invention and shown as connecting two, three-wire cables.

Fig. 2 is a face view of the male portion of my connector.

Fig. 3 is a face view of the female portion of my connector.

Fig. 4 is a full sectional view of the male portion of my connector taken on the line 4—4 of Fig. 2.

Fig. 5 is a full sectional view of the female portion of my connector taken on the line 5—5 of Fig. 3.

Fig. 6 is a full sectional view taken on the line 6—6 of Fig. 1.

Fig. 7 shows the rear or entrance end of the casing forming a part of my invention and shows the manner in which the same may be spread to facilitate the insertion and removal of the contacts.

Fig. 8 is a section on the line 8—8 of Fig. 4, omitting, however, the clamp. This section shows the manner in which the end of each casing is split.

In the preferred embodiment of my invention,

I provide two parts A and B, which are the male and female parts respectively.

The parts A and B are provided with casings 1 and 2 respectively which may be termed bell-shaped and which are duplicates excepting that the part 1 is provided with a flange 3 which overlaps the end of the casing 2 to prevent or resist the entrance of moisture.

Each casing is a single unit including the diaphragm 4 and forming an integral part of the outer portion of the casing. Each diaphragm 4 is provided with openings 5 through which project the contacts. The casings are formed or moulded preferably from rubber.

Projecting rearwardly from the inner surface of each diaphragm 4 is a barrier 6 which prevents the contacts being forced together in case the connector is run-over by a mine car or mining machine, as the casing being of yieldable material will not offer any resistance to the weight of the car or machine.

Each male contact is provided with a rearwardly projecting part 7 which is drilled to receive the end of a cable held in position by a set screw 8 and is, also, provided with a forwardly slotted projection 9 which is received by the female contact.

The female contact is provided with a portion 10 which is drilled to receive the end of a cable held in place by the set screw 11. The contact is, also, provided with an opening 12 to receive the portion 9 of the male contact. The opening in all contacts is drilled off center as shown in Fig. 6 thus permitting the cable wires to rest more closely to the longitudinal center of the connector.

Each contact is held in place by means of a threaded nut 13. A raised flange 13' (see Figs. 2 and 3) offers additional leakage surface between the various contacts. The nuts 13 are provided with slots 15 by means of which a tool applied thereto may be used to tighten the nuts.

The casings 1 and 2 are split longitudinally as shown at 16 in Figs. 1, 7 and 8 for a considerable distance back from the rear end of the casings. This permits the rear end of the casings to be spread apart so that after the nuts 13 have been removed it is possible to withdraw the contacts through the rear opening with considerable ease.

This is possible since the casing is formed from a rubber which is flexible thus permitting the split ends to be spread apart and due to the elasticity of the rubber the spread ends of the casings have the power to spring back to their normal or original form. The casing may be made from a

tough grade of rubber such as used in auto tires or what is known as "car spring rubber" or any other grade of rubber suitable for the purpose described. I do not wish to be limited to the use of rubber per se as there are a number of synthetic products which may be used; therefore, the term "rubber" is to include such other materials as are suitable for my invention.

Having removed the contacts the ends of the cable are inserted in the opening therein and the screws 8 and 11 manipulated to hold the cable in place. In the drawing the cables 17 are shown as having three insulated conductors and the connector is shown with each part having three contacts, if desired the connector may be made with either one or two contacts or any number of contacts as required by the number of conductors in the cable.

After the contacts have been assembled to the end of the conductors the end of the casing is spread apart as shown in Fig. 7 and the contacts repositioned in the openings in the diaphragm 4. The spread end of the casing is then allowed to spring back into normal position as shown by the dotted lines in Fig. 7 and the nuts 13 reassembled on the contacts. A screw clamp 18 is applied to the rear end of each part A and B for the purpose of holding the split parts of the casing in normal position and also to securely clamp the casing onto the cable 17 thus insuring a waterproof interior of the casing and preventing any pull of cable conductors upon the contacts which would tend to break the connection. If the cable 17 should be under-sized then the usual practice is to apply sufficient tape to the outside of the cable to bring it up to a size where the casing will clamp securely thereto.

The device is subjected to very rough usage in a mine as it may be dragged considerable distances over the rough floor of the mine by a mining machine to which one end of the cable is attached. In order to prevent the parts A and B separating under such usage, I employ means for holding the parts together consisting of the chain and toggle arrangement C which is attached to screws or rivets 19 and 19'. The free end of the chain portion 20 is fixed to its screw 19 while the free end of the toggle portion 21 is provided with a hook which engages with its screw 19'.

The toggle portion 21 is provided with a lever 22 pivoted to the hook portion 23 at 24. Pivoted to the portion 22 at 25 is the link 26. When the lever 22 is moved clockwise about the pivot 24 the pivot 25 and link 26 move downwardly and to the left thereby lengthening holding means C and permitting the portion 23 to be unhooked from the screw or rivet 19' thus permitting the parts A and B to be separated. Having placed the parts A and B together the hook of the member 23 is then attached to the screw or rivet 19' and the lever 22 moved anti-clockwise about the pivot 24 which shortens the chain and toggle C thus holding the parts A and B together, preferably with a slight compression which prevents the entrance of moisture and the short-circuiting of the contacts along the face of the diaphragm.

By clamping each casing to its cable by means of the clamps 18 and connecting the clamps by the flexible chain connection 20, I am able to relieve the connector of all strain in tension tending to break the connection of the conductors to the contacts, to hold the parts A and B together under compression and to prevent separation of

the parts A and B and distortion of the casings.

In order to prevent misconnections, I prefer to color the face of the flanges 13' to correspond to the color of the insulation on the individual wires as provided by the manufacturer of the cable. In one instance the face of the flanges 13' would be colored red, white and black respectively.

In order to properly connect the parts A and B, I provide on the flange 3 of the part A a slightly raised or depressed indicator 27 and on the part B directly opposite the indicator 27, I provide a similar indicator 28, both moulded as a part of the casings, and when these indicators are positioned opposite each other the conductors will be properly connected.

If desired, when there are two or more contacts on each part A and B, a part of the contacts on one part may be male and the balance female, and the contacts on the other part also changed to cooperate with those on the first part. This arrangement of contacts will also prevent wrong connecting.

The diaphragm 4 of the casings being elastic and flexible, there is little if any difficulty in bringing the male and female parts together for the reason that the diaphragm is yieldable to any reasonable differences.

The slot or cut 16 is shown as curved in Fig. 8 as I find this to be more satisfactory and efficient than where the cut is radial; there is more resistance to the entrance of moisture thus effected.

I have arranged to lock the connector parts against malicious disconnecting or for other reasons by providing the member 26 with a hole 30 in which may be hooked a padlock (not shown), thus preventing operating the toggle lever 22 to its open position.

I wish it to be understood that I do not desire to be limited to the exact details of construction shown and described for obvious modifications will occur to a person skilled in the art.

I claim:

1. A connector for a plurality of conductors comprising a pair of connector parts, each part comprising a one-piece casing of elastic, flexible, deformable material provided with a diaphragm at one end forming with the casing side wall a receptacle, the casing having a passage at the other end through which a cable may be passed, the casing being split for a distance back from the end to permit spreading the end thereof for convenient access to the receptacle, openings through each diaphragm, a contact positioned in each opening and projecting inwardly from the diaphragm into the receptacle and having an externally exposed portion, the externally exposed contact portions of one casing projecting outwardly beyond the outer end face of the casing and cooperating with those exposed contact portions on the other casing to form a complete electrical connector between the connector parts, each contact provided with means on its inwardly projecting portion to receive and hold a conductor end and means to hold the split end of each casing in normal condition, the said means comprising an adjustable clamp about the split end of each casing whereby the casing may be drawn into engagement with the cable to anchor the casing to the cable and close the slit in the casing, flexible means connecting the clamps and means connecting the flexible means to one clamp whereby the means may be drawn taut to hold the

connector parts in connected relation and under compressive stress.

2. A connector for a plurality of conductors comprising a pair of connector parts, each part comprising a one-piece casing of elastic, flexible, deformable material provided with a diaphragm at one end and a recess, an opening at the other end of the casing opening into the recess, the casing being split for a distance back from the end to permit spreading the end for convenient access to the recess, openings through each diaphragm, a contact positioned in each opening and projecting inwardly from the diaphragm into the recess and having an externally exposed portion, the externally exposed contact portions of one casing projecting outwardly beyond the outer end face of the casing and cooperating with those contacts on the other casing to form a complete electrical connector between the connector parts, each contact provided with means on its inwardly projecting portion to receive and hold a conductor end, adjustable clamping means surrounding the end of each casing to draw the slit faces of the casing together to prevent entrance of moisture and to hold the split end of each casing in engagement with the cable extending therethrough to prevent slippage between the cable and casing and adjustable and flexibly formed means connected to and mechanically connect-

ing the clamping means to prevent the connector parts separating and to hold the faces of the connector parts under compression.

3. In a connector for an electric cable of one or more conductors comprising a pair of connector parts, each part comprising a one-piece recessed casing of elastic, flexible and deformable material provided with a sleeve at one end, a passage through the sleeve opening into the recess for the entrance of the cable end into the recess, each connector part provided with one or more contacts cooperating with contacts on the other connector part and to which contact or contacts the conductor of the cable is attached, the combination with the said sleeves of means to clamp the sleeves onto the cable to anchor the sleeves to their respective cable to resist longitudinal movement of the cable relative to its sleeve and to hold the connector parts from separating, the said means comprising an adjustable clamp encircling each sleeve whereby the sleeve may be drawn into engagement with its cable to anchor the sleeve to the cable and flexible means connecting the clamps, the means connecting the flexible means to one clamp arranged to draw the flexible means taut to hold the connector parts in connected relation and under compressive stress.
